UNITED STATES PATENT OFFICE.

FRANK HEDLEY, OF YONKERS, AND JAMES S. DOYLE, OF MOUNT VERNON, NEW YORK.

PASSAGeway-CONTROL MECHANISM.

Application filed December 28, 1920. Serial No. 433,693.

This invention relates to passageway control mechanism.

The object of the invention is to provide means for controlling the passage of persons 5 through a passageway, which control means are simple in structure and efficient in operation.

A further object of the invention is to provide controlling mechanism for a restricted passageway which permits the passage of persons through the passageway in either direction but effects registrations of such passages in one direction only.

A further object is to provide a controlling 15 mechanism of the nature referred to which permits both entrance and exit operation, but effects registration of the entrance operation only.

A further object is to provide a controlling 20 mechanism for both entrance and exit passage through a restricted passageway, in which the entrance passages only are coin controlled.

A further object is to provide barrier arms 25 for a restricted passageway which are normally locked and which are released by the deposit of a coin.

A further object is to provide barrier arms 30 for a restricted passageway and electrically operated locking devices therefor, the operating circuit of which locking devices is controlled by the deposit of a coin.

A further object is to provide electrically 35 operated locking devices for the barrier arms of a restricted passageway, the operating circuit of which locking devices is controlled by the passage of a person through the passageway.

Other objects of the invention will appear 40 more fully hereinafter.

The invention consists substantially in the construction, combination, location, and relative arrangement of parts, all as will be more fully hereinafter set forth, as shown in the 45 accompanying drawings, and finally pointed out in the appended claims.

In the accompanying drawings,—

Fig. 1 is a view in top plan of a restricted 50 passageway control mechanism embodying the principles of our invention.

Fig. 2 is a view in side elevation looking towards the left hand side of Fig. 1.

Fig. 3 is a view in section on the line 3, 3, 55 Fig. 2, looking in the direction of the arrows.

Fig. 4 is a view in elevation, parts broken off, and parts in section to show the lock mechanism for the barrier arm shafts, the shaft carrying the entrance arm being shown locked. 60

Fig. 5 is a view in front elevation looking in the direction of exit passage.

Fig. 6 is a detail view showing, detached, the centering cams for a barrier arm shaft. 65

Fig. 7 is a broken view in elevation of the inner face of one side of the passageway control mechanism. 65

Fig. 8 is a broken view in section on the line 8, 8, Fig. 7.

Fig. 9 is a broken detail view in perspective showing the arrangement of switches controlled by the operation of the floor mats. 70

Fig. 10 is a circuit diagram to illustrate the electrical operation and control of the apparatus. 75

Figs. 11 and 12 are similar diagrams illustrating slight modifications in the circuit arrangements.

The same part is designated by the same reference numeral wherever it occurs 80 throughout the several views.

The problem of efficiently controlling the entrance and exit of passengers to and from transportation systems, such as surface, subway and elevated street car systems, ferries, or the like, as well as the entrance and exit of patrons to theatres, amusement parks, &c., and effecting the collection of the fares or entrance fees from, and securing registrations thereof is of constantly increasing 90 difficulty with the increasing demands and requirements of modern rapid transit and the increasing numbers of passengers or persons to be handled. Among the most important of the requirements may be mentioned that of speed in handling and controlling the entrance and exit operations; accuracy and certainty of fare or entrance fee collection and registration; the necessity for insuring a fare or entrance fee collection for each individual effecting an entrance passage; and relative freedom and ease of entrance and exit movements with the least possible obstruction under normal conditions but efficient resistance in case of attempted unauthorized entrance operation. 95

Various expedients have heretofore been proposed and employed for accomplishing these purposes, but the modern demands and requirements have exceeded the capacity of 105

110

the arrangements now generally employed, and have rendered such arrangements inefficient and inadequate.

Our present invention relates to apparatus of this general nature, and in carrying out the same we propose to employ a restricted passageway which may be used both for entrance and exit operation, the said operations being suitably controlled so as to permit only 10 one person at a time to pass through such passageway, the exit operation or movement being rendered practically free and unobstructed while the entrance operation or movement is controlled in such manner as 15 to insure fare or entrance fee collection and registration for each person effecting such entrance use of the passageway.

In a somewhat more restricted statement of the nature of the principles of our invention, we propose to employ two sets of barrier arms for a restricted passageway arranged to operate in successive order, whether for entrance or for exit movement. One of these sets, for convenience, we will 25 designate as entrance barriers or arms, and the other as exit barriers or arms, and we propose to employ alternately operating locking devices for these barriers. That is, locking devices which are controllable to 30 alternately lock and unlock both sets of barriers, so that when one set is locked the other set is unlocked, and, under normal conditions the entrance barriers are maintained locked while the exit barriers are unlocked. For entrance operation the locking 35 devices are controlled by the deposit of a coin or token to release the entrance and lock the exit barriers. The return of the entrance barriers to normal position after 40 the person entering has passed beyond the entrance barriers causes an automatic release of the exit barriers and the locking of the entrance barriers. The deposit of the coin or token to effect the release of the 45 entrance barrier also effects a registration. For exit operation, the exit barrier is first operated, being normally unlocked, and the passage through the passageway of a person in exit direction effects a release of the 50 lock of the entrance barrier. These various operations in one form of practical embodiment of our invention are effected and controlled electrically, the electric circuit arrangements employed being controlled by 55 the deposit of coins, or tokens, the operation or displacement of the barriers, and by the movement of persons through the 60 passageway, all as will be more fully set forth hereinafter.

Referring to the drawings wherein we have shown one practical and operative embodiment of our invention, and which, in practical use has demonstrated its effectiveness, reference numeral 50 designates a restricted passageway, see Fig. 5, which, in

this instance, is formed by means of the railings 13, 13, placed in parallel relation to each other and spaced apart the required distance to form the passageway 50 between them of the desired width to comfortably 70 accommodate a single person. The railings 13 are supported at their ends in any convenient manner, as by posts 14.

Disposed at opposite sides of the passageway are the frames 15, in the opposite 75 ends of each of which are journaled the vertical shafts 16, 17, respectively carrying barrier arms 18, 19, which form respectively, the entrance and exit barriers across the restricted passageway 50.

Upon the shafts 16, 17, are mounted a series of insulating members 20 upon which are mounted contact strips for cooperation with contact fingers employed in the circuit system of the apparatus. For illustration 85 the insulating members 20 on shafts 16 carry, respectively, the contact strips 21, 22, and 23, the latter being in duplicate and disposed on opposite sides of their cooperating fingers for a purpose presently to be explained. Cooperating with the contact strips 21, 22 and 23, are, respectively, the fingers 24, 25 and 26. The insulating members 20 of the shafts 17, likewise, respectively, carry contact strips 27, 28 and 29, 95 with which, respectively, cooperate the fingers 30, 31, 32. The various contact fingers 24, 25, 26, 30, 31, 32, are carried by a supporting member 33, mounted on the frame 100 15.

Mounted on each shaft 16, 17, is a collar with which cooperates a locking bar. It will be understood that each side frame 15 supports a shaft 16, and a shaft 17 respectively, carrying an entrance and an exit 105 barrier 18, 19. We, therefore, arrange a locking mechanism which operates to alternately lock and unlock the shafts 16 and 17 on the same side of the passageway. The locking collars on these shafts are shown 110 in Fig. 4, as designated, respectively by reference numerals 34, 35, and the cooperating locking bar by reference numeral 36, which, when shifted in one direction, engages in locking collar 34 to lock the entrance barrier shaft 16, while the same movement of said bar withdraws it from locking engagement with collar 35. The locking bar 36 is mounted and guided in the side frame 15, and is shown in Figs. 2, 3 and 4, in engagement with the locking collar 34 of the entrance barrier shaft 16, and out of engagement with the collar 35 of the exit barrier shaft 17. This is the normal position of the 115 locking parts and consequently the entrance barriers are normally locked against displacement in both entrance and exit operation, while the exit barriers are normally released and free for operation in either 120 direction.

The movements and control of the locking bar may be effected in many different ways. We have shown a simple arrangement wherein said bar is engaged by crank arms 37, on a shaft 38, journaled in the side frame 15, and which is rocked by a crank arm connection 39, to the rod 40 of a piston 41, operating in a cylinder 42. The piston is actuated in one direction by pressure medium supplied to cylinder 42 against the action of a spring 43, which tends to move the piston in the opposite direction when the cylinder is opened to exhaust. We do not wish to be limited or restricted to this arrangement for operating the locking bar since it is obvious that said bar may be operated and controlled in various other ways. The arrangement shown, however, is simple and effective in practical operation. The supply and exhaust of pressure medium to and from the cylinders may be controlled in any suitable manner. An efficient arrangement is shown wherein we employ an electro-magnetic valve actuating mechanism 44, the coil of which is indicated at 45 in the circuit diagram views, Figs. 10, 11 and 12.

It is desirable to provide means to yieldingly resist the rotative movements of the shafts 16, 17, in order to insure their return to normal position after being displaced therefrom. It is also desirable to insure a proper centering of the shafts in their normal positions in order that the circuit system controlled by the rotative movements of said shafts may not be deranged by the failure of complete return of the shafts to their normal positions. These results may be accomplished in various ways. We have shown a simple arrangement which we have found efficient for the purpose wherein we mount upon each shaft a block 46 having a cam face against which bears a corresponding cam face on a cooperating block 47. The block 47 is yieldingly pressed towards the block 46, by means of a spring 48, but yields against the tension of said spring when the block 46 is rotatively moved, that is, when the shaft is rotated, by reason of the engaging cam surfaces of said blocks. The blocks 47 are held against rotative movement while permitted movement towards and from the blocks 46, by means of arms 49, carried thereby, which work in vertical slots 51 in an adjacent bracket 52.

Thus we provide a combined returning and centering mechanism for the barrier shafts which insure the return of the shafts, when displaced, to their normal positions and which insure the proper centering of said shafts in their normal positions.

Various arrangements may be employed to effect control of the circuit system of the apparatus by the movement or passage of persons through the passageway. A simple

arrangement is shown wherein we provide movable portions 53, 54, in the flooring of the passageways. These movable portions are normally maintained slightly raised, as, for example, by means of springs 55, so as to be depressed by the weight of a person imposed thereon. The movements of these movable mats or floor portions are employed to control circuit contacts 56, 57, 59, through suitable adjustable rods 60, see Figs. 7 and 9, and levers 61, pivotally mounted on a convenient part 62 of the frame.

Adjacent the entrance end of the passageway 50 is a fare or coin box 63 into which the required fares, coins or tokens are to be deposited, and which, when deposited, control the circuit of a magnet coil 64, said magnet coil in turn controlling circuit contacts 65, 66, 67, the contacts 65 being closed and the contacts 66 and 67 being open when the magnet coil 64 is deenergized, and said contacts 65 being opened and contacts 66 and 67 being closed when said magnet coil is energized.

In the control of the circuit system for exit operation we employ a relay magnet 68, the coil 69 of which is diagrammatically illustrated in the circuit diagrams, Figs. 10, 11 and 12. This relay magnet, when energized, closes circuit contacts 70, 71, for a purpose to be more fully explained hereinafter.

We will now describe the operation of the apparatus and the circuit system and control therefor, assuming the parts to occupy their normal positions ready for use for either entrance or exit operation, and we will first describe the operation and control for entrance operation. Under these conditions it will be understood that the entrance arms, or the shafts carrying them, are locked against operation in either direction while the exit arms, or their shafts, are free for operation in either direction.

Now a person approaching the entrance end of the passageway deposits a coin in the coin box 63. This completes a circuit from trolley or other current source A, through wire a, fingers 30 and contact strips 27, wire b, coils 45 of the lock magnets, floor controlled contacts 57, which are normally closed, wire d, the coin at 72, to ground at 73. The closing of this circuit energizes the lock control coils 45, thereby unlocking the entrance barriers and locking the exit barriers. The person then enters the passageway displacing the entrance barriers, which are now unlocked, thereby rotating the shafts 16, in entrance direction, against the action of the resisting springs 48. The displacement of the shafts 16, causes contact strips 21 to bridge the contacts 24, thereby completing the following circuit: from trolley or current source B, through wire e, the fare box coil 64, wire f, 130

wire *g*, contacts 24, strip 21, wire *d*, coin 72, to ground at 73. The completion of this circuit energizes the fare box coil 64, which results in closing contacts 66 and 67, and opening contacts 65. The closing of contacts 67, establishes a holding circuit for magnet coil 64, from wire *f*, through contacts 67, to ground at 74, thus being rendered independent of the strips 21, and contacts 24, as well as of the coin 72, and consequently the entrance barrier arms are free to return to their initial position, and the coin is free to pass on into the fare box, without affecting the circuit of the fare box coil 64. The closing of the contacts 66 maintains the circuit of the lock magnet coils 45 closed independently of the coin 72, from wire *d*, contacts 66, to ground at 75, and consequently the coin is free to pass on into the fare box without affecting the circuit of the lock magnet coils 45. The energization of fare box coil 64 actuates in any well known manner a register mechanism indicated at 76. The entrance barriers having been passed and having returned to their normal positions, the entering person proceeds towards the exit barriers and in doing so steps upon the floor mat or section 54, thereby opening the contacts 57 and closing the contacts 56. The opening of contacts 57 opens the circuit of the lock magnet coils 45, thereby causing the exit barriers to be unlocked and the entrance barriers to become again locked. The entering person is now free to pass on through or past the exit barriers, the displacement of which causes contact strip 29 to bridge the fingers 32. This short circuits the fare box coil 64, from current source B through *h*, contact strips and fingers 29, 32, to ground at 77, thereby restoring the contacts 65, 66 and 67, to normal position. The person then passes on and the exit barriers, which are normally unlocked, are free to return to their normal position.

The operation and control for exit movement through the passageway is as follows: A person approaches and enters the exit end of the passageway displacing the exit barriers before him, these barriers being normally unlocked and free for such displacement. This displacement of the exit barriers towards the entrance end of the passageway causes the contact strips 28, to bridge the fingers 31, while leaving the contacts 29, 32, open. The closing of contacts 28, 31, completes a circuit from trolley or current source H, through contacts 28, 31, wire *j*, to floor controlled contacts 56, which are normally open, but which are closed by the person making the exit passage stepping upon the movable floor mat or section, thence through wire *h*, relay magnet coil 69 to ground at 78. The completion of this cir-

cuit causes contacts 70, 71, to close. The closing of contacts 71, closes a retaining circuit for the relay 69, from current source H, through wire *l*, floor mat controlled contacts 59, wire *m*, contacts 71, coil 69, to ground at 78, so that the relay circuit is no longer dependent upon the displacement of the exit barriers, and said barriers after the person has passed them are free to return to normal position without opening the relay circuit.

The closing of contacts 70, closes a circuit through the lock magnet coils 45, as follows: from current source A, wire *a*, contacts 27, 30, the exit barriers having returned to normal position, wire *b*, coils 45, wire *n*, contacts 70, wire *p*, contacts 22, 25, wire *r*, contacts 65, to ground at 79. The closing of this circuit causes the entrance barrier to become unlocked and the exit barrier to become locked, and the person is now free to pass on out through or past the entrance barriers. When he opens the relay magnet retaining circuit at floor controlled contacts 59 the parts return to their normal position, the lock circuit is opened at 70 and the entrance arms again become locked.

The contacts 23, 26, control a retaining circuit for the lock magnet coils 45. It will be observed that the strips 23 are in pairs and they serve to bridge the fingers 26, when the entrance barriers are displaced in either entrance or exit operation, so that when said barriers are displaced, circuit through the lock coils 45 is closed from A, through *a*, contacts 27, 30, coils 45, *n*, contacts 23, 26, to ground at 80. This insures the locking of the exit barriers until the entrance barriers return to normal.

In Fig. 11 we have shown a slightly modified circuit arrangement wherein the deposit of a coin directly completes the circuit of the fare box magnet 64, causing the latter to act to close the circuit of the lock releasing magnets, and also causing the holding circuit for the fare box magnet to be closed, thereby permitting the coin to be released and to drop into the fare receiving receptacle of the fare box. This prevents possible unauthorized tampering or lock release resulting from holding a coin in the coin chute, thereby permitting continuous or repeated entrance operation with a single fare. This arrangement also prevents the possibility of causing registration of an exit operation. The circuit arrangement of this modification is concerned principally with the circuit of the fare box magnet. This circuit may be traced from trolley or other current source at B, through *e*, coil 64, wire *a'*, auxiliary floor mat or tread contacts 80', which are normally closed, wire *f'*, coin 72, to ground at 73. The closing of this circuit closes contacts 67 and 66. The closing of 67, closes a holding circuit for magnet 64, to

ground at 74. This maintains magnet 64 energized until it is short circuited at 29, 32, as before explained. The closing of contacts 66, completes the circuit of the locking magnets from A, through a, 30, 27, b, 45, c, 57, d, 66 to ground at 79.

In other respects the arrangement and operation is the same as before described.

In this arrangement contact 65 of the first 10 system is dispensed with and its function is performed by contact 70.

The circuit arrangement shown in Fig. 12 is substantially the same as that shown in Fig. 11 except that instead of shorting the 15 fare box relay circuit, this circuit is opened by the operation of the exit arms, the contacts 82, 83, controlled by the exit arms being included directly in the circuit of the fare box magnet.

From the foregoing description it will be seen that we have provided an exceedingly efficient and simple means for controlling the passage of persons through a restricted passageway wherein persons may pass in either 25 direction through the restricted passageway and registration of such passages therethrough effected for passages in one direction only. It will also be seen that passage through the restricted passageway in one 30 direction is coin controlled, such passageway being normally locked, the release of the lock being effected by the deposit of a coin. Moreover, it will also be seen that the passage of a person through the restricted passageway effects the displacement of barriers opposing such passageway, which barriers, when displaced, effect in various ways, the control of the locking devices for such barriers; also the passage of a person through 35 such passageway is employed by utilizing such passage for the progress of a person through the passageway to effect control of the apparatus. Obviously, if desired, a proper token might be used in place of the 40 coin.

It will also be seen that we provide an apparatus of this nature which permits the easy and speedy handling and controlling of entrance and exit operations with accuracy 45 and certainty of fare or entrance fee collection and registration as well as freedom and ease of passage in either entrance or exit operation with the least possible obstruction under normal conditions, but with efficient resistance in case of attempted unauthorized entrance operation.

Having now set forth the objects and nature of our invention and various arrangements embodying the principles thereof, what we claim as new and useful and of our 50 own invention and desire to secure by Letters Patent is,—

1. In a passageway controlling apparatus, 55 means to form a restricted passageway, in combination with barriers for said passage-

way, said barriers being free for operation in one direction, locking devices for locking said barriers against operation in the opposite direction, and electropneumatic means for releasing said locking devices. 70

2. In a passageway controlling mechanism, means to form a restricted passageway in combination with barriers for said passageway, said barriers being free for operation in one direction, locking devices for 75 locking said barriers against operation in the opposite direction, electropneumatic means for releasing said locking devices, a circuit for said electropneumatic means, and coin controlled devices for said circuit. 80

3. In a passageway controlling mechanism, means to form a restricted passageway in combination with barriers for said passageway, locking devices for said barriers, electropneumatic means for controlling said 85 locking devices, a circuit for said electropneumatic means, coin controlled devices for said circuit, and means controlled by a passageway barrier for also controlling said circuit. 90

4. In a passageway controlling mechanism, means to form a restricted passageway in combination with barriers for said passageway, locking devices for said barriers, electropneumatic means for controlling said 95 locking devices, a circuit for said electropneumatic means, coin controlled devices for said circuit, and means controlled by a person passing through said passageway for also controlling said circuit. 100

5. In a passageway controlling mechanism, means to form a restricted passageway in combination with barriers for said passageway, locking devices for said barriers, electropneumatic means for controlling said 105 locking devices, a circuit for said electropneumatic means, coin controlled devices for said circuit, and a movable member associated in said passageway and operated by a person traversing the passageway for 110 also controlling said circuit.

6. In a passageway controlling mechanism, means to form a restricted passageway, in combination with barriers for said passageway, electropneumatically operated 115 devices for locking said barriers, coin operated devices for controlling said electropneumatic devices, means controlled by the displacement of a barrier of said passageway for also controlling said electropneumatic devices, and means operated by a person traversing said passageway for also controlling said electropneumatic devices. 120

7. In a passageway controlling mechanism, means to form a restricted passageway, 125 barriers disposed at opposite ends of said passageway, locking devices for said barriers, means whereby when the locking device for one of said barriers is released, that for the other is in locking relation, and 130

coin controlled means to release one of said locking devices.

8. In a passageway controlling mechanism, means to form a restricted passageway, barriers disposed at opposite ends of said passageway, locking devices for alternately locking and releasing said barriers, and coin operated means for controlling said locking devices.

10. 9. In a passageway controlling mechanism, means to form a restricted passageway, barriers disposed at opposite ends of said passageway, locking devices for alternately locking and releasing said barriers,

15. electropneumatically operated devices for controlling said locking devices.

10. In a passageway controlling mechanism, means to form a restricted passageway, barriers disposed at opposite ends of

20. said passageways, locking devices for alternately locking and releasing said barriers, and means controlled by the displacement of one of said barriers for controlling said locking devices.

25. 11. In a passageway controlling mechanism, means to form a restricted passageway, barriers disposed at opposite ends of said passageway, locking devices for alternately locking and releasing said barriers,

30. and movable means associated with said passageway and operated by a person traversing the same for controlling said locking devices.

35. 12. In a passageway controlling mechanism, means to form a restricted passageway in combination with barriers for said passageway disposed at opposite ends thereof, a locking bar shiftable into position to lock one of said barriers and to release the

40. other when moved in alternate directions, and means for controlling said locking bar.

45. 13. In a passageway controlling mechanism, means to form a restricted passageway in combination with barriers for said passageway disposed at opposite ends thereof, a locking bar shiftable into position to lock one of said barriers and to release the

50. other when moved in alternate directions, and coin controlled devices for controlling said locking bar.

55. 14. In a passageway controlling mechanism, means to form a restricted passageway in combination with barriers for said passageway disposed at opposite ends thereof, a locking bar shiftable into position to lock one of said barriers and to release the

60. other when moved in alternate directions, and means controlled by the displacement of one of said barriers for controlling said locking bar.

65. 15. In a passageway controlling mechanism, means to form a restricted passageway in combination with barriers for said passageway disposed at opposite ends thereof,

one of said barriers and to release the other when moved in alternate directions, and means controlled by the passage of a person through the passageway for controlling said locking bar.

70. 16. In a passageway controlling mechanism, means to form a restricted passageway in combination with barriers for said passageway disposed at opposite ends thereof, a locking bar shiftable into position to 75 lock one of said barriers and to release the other when moved in alternate directions, a cylinder having a piston connected to said locking bar for actuating the same, and means for controlling the supply and exhaust of an operating fluid to and from said cylinder.

75. 17. In a passageway controlling mechanism, means to form a restricted passageway in combination with barriers for said 80 passageway disposed at opposite ends thereof, a locking bar shiftable into position to lock one of said barriers and to release the other when moved in alternate directions, a cylinder having a piston connected to said 85 locking bar for actuating the same, and coin controlled devices for controlling the supply and exhaust of an operating fluid to and from said cylinder.

90. 18. In a passageway controlling mechanism, means to form a restricted passageway in combination with barriers for said 95 passageway disposed at opposite ends thereof, a locking bar shiftable into position to lock one of said barriers and to release the 100 other when moved in alternate directions, a cylinder having a piston connected to said locking bar for actuating the same, and means controlled by the displacement of one of said barriers for controlling the supply and exhaust of an operating fluid to and from said cylinder.

105. 19. In a passageway controlling mechanism, means to form a restricted passageway in combination with barriers for said 110 passageway disposed at opposite ends thereof, a locking bar shiftable into position to lock one of said barriers and to release the other when moved in alternate directions, a cylinder having a piston connected to said 115 locking bar for actuating the same, and means associated with said passageway and operated by the passage of a person there-through for controlling the supply and exhaust of an operating fluid to and from said 120 cylinder.

125. 20. In a passageway controlling mechanism, means to form a restricted passageway, barriers for said passageway and disposed at opposite sides thereof, the barriers at each side of said passageway being disposed respectively at opposite ends of said passageway, a locking bar for the barriers at each side of the passageway and common to the barriers at opposite ends of 130

the passageway, and means to operate said locking bar to lock one of said barriers and to release the other.

21. In a passageway controlling mechanism, means to form a restricted passageway, barriers for said passageway and disposed at opposite sides thereof, the barriers at each side of said passageway being disposed respectively at opposite ends of said passageway, a locking bar for the barriers at each side of the passageway and common to the barriers at opposite ends of the passageway, and coin controlled devices for controlling said locking bar operating means.

22. In a passageway controlling mechanism, means to form a restricted passageway, barriers for said passageway and disposed at opposite sides thereof, the barriers at each side of said passageway being disposed respectively at opposite ends of said passageway, a locking bar for the barriers at each side of the passageway and common to the barriers at opposite ends of the passageway, and means controlled by the displacement of one of said barriers for controlling said locking bar operating means.

23. In a passageway controlling mechanism, means to form a restricted passageway, barriers for said passageway and disposed at opposite sides thereof, the barriers at each side of said passageway being disposed respectively at opposite ends of said passageway, a locking bar for the barriers at each side of the passageway and common to the barriers at opposite ends of the passageway, means controlled by the passage of a person through the passageway for controlling said locking bar operating means.

24. In a passageway controlling mechanism, means to form a restricted passageway in combination with a barrier for said passageway, a shaft carrying said barrier, and means to resist the rotative movements of said shaft in either direction without longitudinal displacement of said shaft or barrier, said means operating to center said shaft in normal position, said means including blocks having engaging cam surfaces, one of said blocks being mounted on said shaft, the other yieldingly displaceable longitudinally of said shaft.

25. In a passageway controlling mechanism, means to form a restricted passageway in combination with a barrier for said passageway, a shaft carrying said barrier, and means to resist the rotative movements of said shaft in either direction without longitudinal displacement of said shaft or barrier, said means operating to center said shaft in normal position, said means including blocks having engaging cam surfaces, one of said blocks being mounted on said shaft, the other yieldingly displaceable

longitudinally on said shaft, and means to prevent rotative movement of said displaceable block.

26. In a passageway controlling mechanism, barrier devices spaced apart from each other in the direction of length of the restricted passageway, means normally operating to lock one of said barriers, the other barrier being free, means to release the locked barrier and to lock the free barrier, means operated by the passage of a person through the released barrier and the passageway for releasing the lock of the free barriers, said means operating to again lock the normally locked barrier.

27. In a passageway controlling mechanism, entrance and exit barriers, said entrance barriers being normally locked and said exit barriers normally free, a relay magnet, a circuit therefor, means operated by the displacement of the free exit barriers when operated in exit operation for closing the circuit of said relay magnet, contacts actuated by the energization of said relay, said contacts controlling a holding circuit for said relay independently of the barrier control circuit of said relay.

28. In a passageway controlling mechanism, entrance and exit barriers, said entrance barriers being normally locked and said exit barriers normally free, a relay magnet, a circuit therefor, means operated by the displacement of the free exit barriers when operated in exit operation for closing the circuit of said relay magnet, contacts actuated by the energization of said relay, said contacts controlling a holding circuit for said relay independently of the barrier control circuit of said relay, and contacts arranged in said holding circuit, said contacts controlled by the passage of a person through the passageway in exit operation.

29. In a passageway controlling mechanism, entrance and exit barriers, said entrance barriers being normally locked and said exit barriers normally free, a relay magnet, a circuit therefor, means operated by the displacement of the free exit barriers when operated in exit operation for closing the circuit of said relay magnet, contacts actuated by the energization of said relay, said contacts controlling a holding circuit for said relay independently of the barrier control circuit of said relay, a movable member associated with said passageway and operated by the passage of a person therethrough, said movable member controlling said holding circuit.

30. In a passageway controlling mechanism, entrance and exit barriers, said entrance barriers being normally locked and said exit barriers normally free, a relay magnet, a circuit therefor, means operated by the displacement of the free exit barriers when operated in exit operation for closing

the circuit of said relay magnet, contacts actuated by the energization of said relay, said contacts controlling a holding circuit for said relay independently of the barrier control circuit of said relay, a yielding floor member for said passageway, and contacts arranged in said holding circuit and controlled by said yielding floor member.

31. In a passageway controlling mechanism, entrance and exit barriers, said entrance barriers being normally locked, and said exit barriers normally free, a relay magnet, a circuit therefor, means actuated by the operation of the free exit barrier in exit operation for controlling the circuit of said relay, contacts controlled by said relay, a lock controlling circuit including said contacts to release the lock of the entrance barrier and to lock the exit barrier, and means operated by the entrance barriers in exit operation for controlling the lock circuit.

32. In a passageway controlling mechanism, entrance and exit barriers, said entrance barriers being normally locked, and said exit barriers normally free, a relay magnet, a circuit therefor, means actuated

by the operation of the free exit barrier in exit operation for controlling the circuit of said relay, contacts controlled by said relay, a lock controlling circuit including said contacts to release the lock of the entrance barrier and to lock the exit barrier, and means operated by the entrance barriers in exit operation for controlling the lock circuit, and floor controlled contacts controlling the relay circuit.

33. In a passageway controlling mechanism, entrance and exit barriers, said entrance barriers being normally locked and the exit barriers normally free, locking devices for said barriers, means to release the lock for the entrance barriers, said means operating to lock the exit barriers, and means to maintain the exit barriers locked, said means controlled by the operation of the entrance barriers.

In testimony whereof we have hereunto set our hands on this 23d day of December A. D. 1920.

FRANK HEDLEY.
JAMES S. DOYLE.
